CORPSE VIEWING COVER

Manuel Rubio Mejia, Yauco, P. R.

Application October 3, 1947; Serial No. 777,621

3 Claims.

(Cl. 27—1)

1

This invention appertains to novel and useful improvements in mortuary equipment.

An object of this invention is to cover a slab adapted to support a corpse by means of a transparent member and interposed between the transparent member and the slab, a closure consisting of a covered frame, the frame including a base member and a pair of arcuate struts, the arcuate struts being connected with the base member or base by means of a pair of arms fixed for pivotal movement to said arcuate struts and operatively connected with a shaft, the shaft being supported for rotation by the base of the frame and projecting through a suitable opening in the transparent cover whereby operation of the arcuate struts may be effected from the outside of the transparent cover.

Other objects and features of novelty will become apparent to those skilled in the art, in following the description of the preferred forms of the present invention, illustrated in the accompanying drawings, wherein:

Figure 1 is a perspective exploded view of the mortuary equipment forming the present invention;

Figure 2 is a longitudinal sectional view of the invention disclosed in Figure 1;

Figure 3 is an enlarged fragmentary perspective view of the actuating means utilized for the purpose of adjusting the closure;

Figure 4 is a fragmentary perspective view of the details of construction shown in Figure 3, showing the same in a second operative position;

Figure 5 is a sectional view of the invention shown in Figure 3 and taken on the line 5—5 and in the direction of the arrows;

Figure 6 is a perspective view illustrating a detail of construction utilized in conjunction with securing the closure to the slab, and;

Figure 7 is a modification of a selected element of the invention.

This invention has been conceived and developed for the purpose of providing an improved mortuary apparatus for use in protecting and reviewing corpses. A specially provided slab is provided as a recipient of a suitable foundation whereon the corpse is positioned. A closure having feasibly adjustable arcuate struts for reviewing a portion of the corpse is provided on the said slab. Then, a cover of transparent material is provided over the said closure and means for actuating the arcuate struts of the closure extends through this last mentioned cover.

2

A slab indicated at 10 is provided of any suitable material and a peripheral recess or flange 12 extends therearound. Seated on the said slab 10 is closure means for covering and protecting a corpse. This closure means is preferably composed of a base or frame 14 which may be made of any suitable material, preferably metallic. Arcuate struts 16 and 18 respectively are secured to the base portion of the frame, while arcuate struts 20, 22 and 24 respectively are pivotally connected with the base portion 14.

A suitable flexible shroud 26 is suitably secured to the said frame, as by folding the marginal edges over selected elements of the said frame and stitching the said shroud in place.

A shaft 28 extends through a suitable bracket

30 which is rigidly secured to the base portion of the frame 14. Also secured to the said shaft

28 is a pair of arms 32 and 34 respectively. These arms 32 and 34 are pivotally connected with the terminal portions of the arcuate struts 20 and 22. A spring 36 extends across the said terminal portion of the arcuate struts 20 and

22 and is secured at the pivot pins associated therewith. This spring normally biases the arcuate struts 20 and 22 to the selected, closed position. Referring to Figures 3 and 4 it will be noted that the spring retains the arcuate struts 20 and 22 in the closed position however,

due to the nature of the structure described above, when the arcuate struts 22 and 20 are forced in the open position, they may be retained at this open position by means of friction in the bearings and also by the positioning of the said terminal portions. It is noted that the said terminal portions are curved

slightly to form crank ends and as the arcuate struts are forced to an open position, the component of force exerted by the spring for returning the said arcuate struts to the closed position diminishes and finally reaches a point which is substantially zero due to the angularity of the said extension.

It is quite apparent from an inspection of the Figures 3 and 4 that the pivoted or hinged arcuate strut 24 is also rigidly secured to the said shaft 28 by means of a pin or the like. It is readily apparent also that upon rotation of the

shaft 28, the arcuate strut 24 will be moved to the desired opening or closing positions. A convenient handle 38 is secured to the said shaft 28 for actuation purposes. A cover 40 is detachably positioned on the said slab 10, engaging

55 the recess or flange 12, aforementioned. An

aperture 42 is provided in the said cover 40 for the purpose of receiving the said shaft 28 therethrough, thereby rendering actuation of the closure means possible from the exterior of the said cover 40. Any suitable material such as certain types of commercial plastic may be utilized in the manufacture of the said cover 40 and any desired configuration may obviously be utilized. However, a preferential configuration is disclosed in Figure 1 for firm seating in the recess 12, the marginal edges of the said cover frictionally engaging the confines of the said recess.

It is noted at this point that the said cover 40 may be substituted by a cover 44 which differs in configuration from the above described member 40. Also, this element or cover 44 may be utilized in lieu of the internal (relative to the cover 40) closure member.

In retaining the said closure member immovable relative to the said slab 10, recesses 48 may be supplied at advantageous positions in the shroud 26 and clips 56 fixed to the lower frame member 14. These clips may obviously be secured to the said slab 10 by any suitable means such as screws 52 or the like.

Of course, the extremities of the pivotally mounted arcuate struts 20, 22 and 24 which are opposite those terminal portions described above, may be disposed on a suitable stub shaft which is journaled in a bracket, identical to that bracket 30 described above.

While there has been described and illustrated but preferred forms of the invention, it is apparent that variations may be made without departing from the spirit of the invention.

Having described the invention, what is claimed as new is:

1. In a mortuary apparatus, a slab and a transparent cover disposed on said slab, said transparent cover having an opening in one side thereof, a closure arranged to form a downwardly opening cavity and disposed on said slab and interposed between said cover and said slab, said closure including a frame having a base

and a plurality of arcuate struts operatively connected therewith, two of said struts being movable with respect to each other and having crank ends, means supporting said movable struts on said base for pivotal movement and including arms pivoted to said crank ends, a shaft mounted for rotation on said base and having one of said arms fixed thereto and the other of said arms rotatively disposed thereon, a spring reacting on the ends of said movable struts and urging said movable struts together in the closed position and opposing the operation of said arms and said shaft, and said shaft being passed through the opening in said transparent cover whereby operation of said shaft may be effected from the outside of said cover.

2. The combination of claim 1 and said closure also including a flexible shroud which is secured to the base and said struts, said shroud being made of two pieces one of which is secured to one of said arcuate movable struts and the other of which is secured to an adjacent arcuate movable strut.

3. The combination of claim 1 and said closure also including a flexible shroud which is secured to the base and said struts, said shroud being made of two pieces one of which is secured to one of said arcuate movable struts and the other of which is secured to an adjacent arcuate movable strut, said slab being flat and having a peripheral recess around the edges thereof, and said transparent cover being disposed in said recess to thereby hold said cover on said slab.

MANUEL RUBIO MEJIA.
